(57) **CLAIM**

The ornamental design for a display screen or portion thereof with graphical user interface, substantially as shown and described.

DESCRIPTION

FIG. 1 is a front view of a display screen or portion thereof with graphical user interface showing a first image in a sequence; and,

FIG. 2 is a front view of a second image thereof. The appearance of the transitional image sequentially transitions between the images shown in FIGS. 1-2. The process or period in which one image transitions to another image forms no part of the claimed design.

The broken line showing of a mobile phone display screen or portion thereof is included for the purpose of illustrating portions of the article and forms no part of the claimed design.
